UNITED STATES PATENT OFFICE.

HERRMANN WOJAN, OF BROOKLYN, NEW YORK.

PIPE-EXPANDER.

SPECIFICATION forming part of Letters Patent No. 377,507, dated February 7, 1888.

Application filed October 5, 1887. Serial No. 251,496. (No model.)

To all whom it may concern:

Be it known that I, HERRMANN WOJAN, of Brooklyn, Kings county, State of New York, have invented a new and Improved Tube-Ex-
5 pander, of which the following is a specifica-
tion.

This invention relates to an expander more particularly designed for curved tubes, inasmuch as the mandrel does not advance into
10 the tube as the latter is expanded. The ex-
pander may, however, also be used on straight
tubes.

The invention consists in the various fea-
tures of improvement more fully pointed out
15 in the claims.

In the accompanying drawings, Figure 1 is
a longitudinal central section on line $x x$, Fig.
2, partly in side view. Fig. 2 is a cross-sec-
tion on line $y y$, Fig. 1. Fig. 3 is an end view
20 of the mandrel looking toward the top of Fig.
1. Fig. 4 is a cross-section on line $z z$, Fig. 1;
and Fig. 5, a perspective view of the sleeve d .

The letter a represents the inclosing cylind-
rical shell of the expander, made with a se-
25 ries of slots for the accommodation of three
fixed expansion-rollers, b , journaled in shell a ,
and of a sliding expansion-roller, c , which will
be hereinafter more fully described. In order
30 to properly journal the fixed rollers in sleeve
 d , the latter should be made sectional, and it
is shown, for this purpose, to be made of a
separable piece or ring, d' , connected to the
shell proper, a , by the screws a' .

For the purposes of this invention the parts
35 a a' will be spoken of, collectively, as the
shell a .

The shell a is provided with a central lon-
30 gitudinal bore or perforation extending from
end to end and concentric to the periphery of
the shell. This perforation accommodates the
eccentric sleeve d . (More fully shown in Fig.
45 5.) This sleeve is formed of two circular heads,
 d' , and of a central connecting-piece, d'' , hav-
ing the cross-section indicated in Fig. 2—that
is to say, the piece d'' is made of gradually-
increasing thickness in cross-section and leaves
the central part of sleeve d open at one side.
One of the heads d' carries a disk, d^3 , which
covers the shell a , as shown.

50 The sleeve d is provided with a longitudinal
bore from end to end, which is eccentric to

the periphery of the sleeve. This bore ex-
tends through the heads d' and disk d^3 , and
its periphery is flush with and a continuation
of the inner curve of piece d'' . The bore ac-
commodates a central mandrel, e , and is pref-
erably slightly conical, as shown in Fig. 1, so
that a conical mandrel may be used. The
mandrel is of course partly exposed between
the heads d' . To prevent longitudinal mo-
tion of the mandrel e , it is coupled at one end
60 to a ring, f , by cross-pin f' , and has at its other
end a shoulder, g , as shown. The disk d^3 has
a slot, d^4 , through which extends the shank of
a thumb-screw, h , engaging shell a . A pair of
65 eyes, $i i$, for the reception of a hand-lever are
also formed on disk d^3 .

j is an annular gage-plate for edging the
tube to be expanded and is secured to the
shell a .

In operating the device a double motion
must be gone through—that is to say, the slid-
ing roller c must be pushed toward the pe-
riphery, and then the expander must be re-
volved to cause an expansion of the tube by
70 such roller. The latter is then again pushed
outward and again the expander is revolved.
Thus the tube is gradually expanded. In or-
der to carry out this operation the screw h is
75 loosened and a lever or pin is introduced into
one of the eyes i . By applying power to this
lever the sleeve d is partially revolved. As
the sleeve is eccentrically bored, it will crowd
the mandrel e out of center, and the mandrel
80 in turn will crowd the roller c partially out of
shell a and toward the circumference of the
tube to be expanded. After the sleeve has
been revolved as far as practicable it is clamped
85 to shell a by screw h . The hand-lever is then
removed and the mandrel e is revolved by in-
90 troducing the lever into a transverse perfora-
tion of such mandrel. The mandrel will by
friction carry the entire expander with it, and
in this way the roller c will travel along the
inner circumference of the tube and expand
95 the same. After the expander has revolved
once or twice the roller c is moved nearer to
the circumference of the tube, in the manner
described, and the expander is again revolved.
Thus it will be seen that the tube is expanded
100 without causing the mandrel to advance into
the same.

What I claim as my invention is—

1. The combination of an outer shell with an inner sleeve eccentrically bored, and with a mandrel passing through said sleeve, and with a sliding roller, substantially as and for the purpose specified.

2. The combination of outer shell, *a*, carrying rollers *b*, with the eccentrically-bored sleeve *d*, and with the mandrel *e* and sliding roller *c*, the sleeve *d* having disk *d*³, provided with

eyes *i*, and with set-screw *h*, substantially as specified.

3. The combination of shell *a* with eccentrically-bored sleeve *d*, cut away at its center, and with fixed rollers *b*, sliding roller *c*, mandrel *e*, and gage-plate *j*, substantially as specified.

HERRMANN WOJAN.
